PAPER UNIT DISPENSING DEVICE

Frank G. Steiner, Chicago, Ill., assignor to Steiner Sales Company, Salt Lake City, Utah, a corporation of Utah

Original application September 16, 1935, Serial No. 40,794. Divided and this application July 29, 1938, Serial No. 221,944

4 Claims. (Cl. 242—55.5)

This invention relates generally to improvements in dispensing cabinets and particularly adapted for dispensing paper drying units.

This application is divisional of my application Serial No. 40,794, filed September 16, 1935 for Paper unit dispensing device.

An important object of the invention is to utilize the curl of the paper resultant from its original roll formation, for maintaining a projected portion of the paper spaced from the wall of the cabinet to facilitate grasping.

Features of the invention include: a dispensing cabinet in which the paper is held spaced in an accessible position as a result of the natural curling tendency of the roll; the utilization of this curling tendency in conjunction with the guiding means for holding the paper in accessible position; means for causing the paper to be delivered in an outstanding and easily accessible position for grasping and spaced from and opposed to the front of the cabinet; and the broader ideas of means inherent in the disclosure which relate to the utilization of the curl of the paper for maintaining a spaced relation to facilitate grasping.

In my application 40,794, of which this application is a division, claim is made to all retails of construction including broader ideas of means relating to the separation of the paper by downward pull.

Objects, features, and advantages of the invention will be set forth in the description of the drawings forming a part of this application; and in said drawings

Figure 1 is a vertical transverse section, taken on line 1—1 of Figure 2, with the drying unit length positioned to be easily grasped and easily severed or separated by a downpull;

Figure 2 is a vertical longitudinal section taken approximately on line 2—2 of Figure 1, with the timer positioned as before setting; and

Figure 3 is a vertical section taken approximately on line 3—3 of Figure 2, with the timer positioned as before setting.

The drawings herein illustrate in addition to the features broadly claimed herein, certain details of construction which also appear in application Serial No. 40,794, these details having been included for the sake of clarity.

In the drawings, numeral 1 generally indicates the outer casing of a cabinet, having a front door 2 hinged at the bottom as at 3 and thus adapted to swing downwardly. The cabinet has a delivery orifice 4 adjacent its top. The lower side of this

orifice is formed by the upper edge 5 of the door 2.

A vertically disposed plate 10 is spaced inwardly from one side wall 11 of the cabinet, and is secured by suitable brackets 12 and 13 respectively to the rear wall 14 of the cabinet and to the side wall 11. This plate defines with the side wall 11 a narrow vertical chamber extending from front to back and substantially from top to bottom of the cabinet, and a larger chamber 10 in which the paper supply roll and feeding and severing means are housed.

Rotatably journaled in the plate 10 and in the opposite side wall 15 of the cabinet is the shaft 16 of a feed roll 17 provided at intervals throughout its length with friction-feeding rings 18 of suitable material, and larger in diameter than the roll so as to project circumferentially therebeyond.

The top wall 20 of the cabinet 1 has a forwardly and outwardly directed down-turned portion 21, the lower edge of which is received by a socket formed in part by a forward rebent portion 22 of a sheet-directing guide. This guide has an arched top portion 23 and a skirt portion 24 extending downwardly in front of the feed roll 17 and lying close to the roll, and having slots or cut-outs 25 forwardly through which the rings 18 extend, as best shown in Figure 1.

Cooperative with the feed roll 18 is a presser roll 27 having a shaft 28 journaled in open end slots 29 respectively of the plate 10 and bracket 30, the bracket 30 being secured to the cabinet wall 15, as best shown in Figure 3. This roll 27 is yieldably urged toward the feed roll 17 and rings 18 by springs 32 acting on the ends of the shaft 28. The paper supply roll is indicated at 35 and from the forward side of this roll the paper is passed upwardly between the roll 27 and the feed rings 18 and against the forward side 40 of the apron 24 and then to the position shown in full lines of Figure 1.

Above the feed presser 27 and forwardly of the roll 17 and under the arch 23 of the guide is arranged a horizontal support generally indicated 36 composed of suitably bent and connected plates. This support is supported by hangers or brackets 39 (see Figure 2) secured to the cabinet sides 11 and 15. The support 36 is detachably secured to the brackets by suitable screws 40. One of the plates of this support carries a toothed knife 41 which is secured to the support by means of nuts and bolts generally indicated at 42, the severing edge of the knife is faced upwardly, and the knife is arranged in opposition to and 55

near the delivery opening 4. The feed roll shaft 16 is provided with an operating crank 45, and after crank-feeding of the paper to the position shown in full lines in Figure 1, the paper is pulled by the user, downwardly to the position shown in dot-and-dash lines of Figure 1 against the toothed tear-off knife, and is thus severed.

The means for causing the paper to be delivered in an outstanding and easily accessible position for grasping and spaced from and disposed to the front of the cabinet is in part or entirely accomplished by taking advantage of the curl of the paper resultant from its original roll formation.

15 It will be noted by inspection of Figure 1 that the paper comes off of the forward side of the supply roll 35 and that it passes upwardly to the feed rolls. The paper does not contact either roll over any substantial surface area thereof but has substantially only a line contact. Thus the paper after passing through the feed rolls retains its curl. After passage through the rolls the forward edge is so guided as to project through the opening in such manner that that 20 face of the paper which was inside when on the roll, faces toward the user and away from the front wall of the cabinet after passing through the delivery opening. As a result of this arrangement of the paper and the character of the feed 25 thereof, the curling tendency is not destroyed and curl is utilized to maintain the projected portion spaced away from the cabinet to facilitate grasping. Of course, the guiding means 23 can alone form the means for causing the paper 30 to be initially directed downwardly and outwardly, but the curling tendency of the paper is utilized to assure that the paper will remain in such an accessible position for grasping.

It is again noted that there is substantially 40 only a line contact between the paper and the rolls. In any event the degree of surface contact is not sufficient to eliminate the curl during passage through the rolls, whereby the forward edge of the freed paper hugs the guide 23 and is guided (in the drawings) first upwardly 45 and then downwardly and outwardly. The curl of the paper causes the forward edge to always hug and ride along the means 23 so that when projected below the upper side of the opening 4, it is pendent and swings outwardly away from the front face of the cabinet. It is evident that the curl will cause this action, providing it is projected downwardly through the orifice. Thus 50 although the guide 23 and its specific location is claimed per se the scheme of preventing destruction of the curl and utilizing the curl and the placing of the parts to obtain curl in the right direction is broadly claimed.

The bend portion of the part 22 of the guide 55 apron forms the upper side of the delivery opening and the upper edge of the door forms the lower side of this delivery opening. This upper edge of the door is suitably rounded to reduce friction.

60 65 To prevent operation of the feed roll in the wrong direction (see dotted lines of Figure 1), a ratchet wheel 50 is provided and placed at one end of the roll and with this ratchet wheel is engaged a pawl 51, see also Figure 3.

70 Means is also provided for feeding a predetermined amount or length of toweling and preventing feed for a predetermined time period following each feeding operation. Referring to Figures 2 and 3: A stop arm 60 is fixed to the shaft 16 at a point between the plate 10 and the

75 wall 11 of the cabinet. This arm acts as a rotative stop and is associated with a sliding stop having the form of a plate 61 suitably slidably operably guided in slot 62 of plate 10. The two stops are connected by a link 63 having a slot 64 through which passes a pin 65 thus slidably and pivotally securing the link to the stop arm 60. The other end of the link is pivotally secured to the plate 61 and in this instance is held by a split key 67.

10 When the roll 17 is rotated in direction of the arrow shown in Figure 3, the arm also moves in that direction and after its lower end has passed to the right of the upper end of the slide stop 61 this stop is raised by means of the link, and 15 after one complete rotation of the roll the parts assume a position in which the plate 61 prevents further rotation of the feed roll, as a result of the end of the arm 60 hitting the plate. The plate is held in stop position after being brought 20 there by the link, in this case by a timer now to be described.

25 The timer is set as the stop plate 61 is moved upwardly from its position in Figure 3. The timer then allows only a slow down motion of the plate 61. The plate 61 of the stop mechanism controls the timer and both are controlled by, and in turn control, the feed roll. For this purpose, the lower end of the plate 61 is bent laterally as at 69 and is operably engaged with a 30 grooved head 70 of the timer stem 71 of a dash-pot type of timer. The barrel of the timer is indicated at 72, this barrel being suitably held by a bracket 73 to the outer side of the plate 10. This type of timer is well known in the art and 35 no further description of it seems necessary. Herein it is merely a symbol of timing means in the general combination.

40 The stem 71 when pulled upwardly and then released, moves downwardly by gravity to assume, at the end of the time period, the position shown in Figure 3, thus moving the element 61 from the path of the element 60 to allow another feeding-out operation of the feeding mechanism.

45 Operation

50 Referring to Figures 1 and 3, and assuming the upper end of the paper to be in the position shown in Figure 3: The operator grasps the crank 45 and rotates the feed roll in direction of the arrow. The roll is given one complete rotation and as a result the paper is fed to a position shown in full lines of Figure 1. During this operation, the arms 60 and 61 move from their positions shown in Figure 3, the link acting to raise the timer stem. The position of the arm 60 and the link at the upper limit of this raising movement is shown in dot-and-dash lines in Figure 3. At the end of this complete rotation of the feed roll 17, timing begins and 55 at the end of the time period the stops again assume the full line position of Figure 3. At the end of the feed-out operation, the user pulls the towel downwardly to the position shown in dot-and-dash lines in Figure 1, whereupon it is severed by the knife, from the remainder of the paper web.

60 65 In order to avoid friction between the slide element 61 and the arm 60 after the parts reach the stop position (which friction would interfere with timer operation), means is provided to back-off the element 60 to the position shown in Figure 3. To this end, a cam 75 is arranged at the end of the roll between the roll and the ratchet wheel 50 and with this cam is engaged, 70 75

see Figure 1, a roller 16, journaled on an arm 77 pivoted as at 78 to the plate 10. Spring 79 urges the arm and roll against the cam and the cam is provided with a projection 80 which is so arranged as to engage the roller and move the roller slightly against the action of the spring. The spring then reacts against this projection to rotate the feed roll in a direction opposite to that shown by the arrow in Figure 3, to the position shown in Figure 3 wherein the arm 60 is spaced from the slide 61 and the latter is free from any frictional contact with the arm 60 so that it may travel downwardly under action of the timer.

15 The supply roll 35 bridges and rests upon narrow friction-reducing strips, a pair 83 of which lie on the bottom 81, and another pair 82 of which extend upwardly against the back wall 14 of the cabinet. It is noted that upward pull on the paper web tends to roll the supply toward the back wall 14 of the cabinet.

The broad feature of this invention as before stated consists in the method and means by which the supply roll is so related to the feeding 25 means and to the delivery orifice of the cabinet that the curl of the paper resultant from its original roll formation is utilized to maintain a projected portion of the paper spaced from the cabinet to facilitate grasping.

30 I claim as my invention:

1. The art of facilitating the grasping of paper after delivery into opposition to the outer face of an upright wall of a cabinet having a delivery opening and feeding means therein by which the 35 paper is delivered through the opening, which consists in first passing the paper through the feeding means, then applying to the paper substantially immediately after it leaves said feeding means a force only against that face of the 40 paper which was inside when on the roll, to automatically gradually flex the paper in a direction opposite to the direction of curl which has been given the paper as the result of roll formation, to form and maintain a free arch between the 45 feeding means and the delivery opening and so that said face which was inside when on the roll constitutes the convex face of said free arch, and then projecting the reversely flexed paper through the opening to a freely pendent position 50 therebelow and in opposition to said upright face, and so that the surface that faced the supply roll faces the user.

2. The art of facilitating the grasping of paper after delivery from a supply roll, by feeding 55 means, to and through an opening, and into opposition to the outer face of an upright wall of a cabinet, which consists, in feeding the paper and while feeding it causing the leading free end of the paper to be so acted upon that the paper is

automatically gradually flexed in a direction opposite to the direction of curl given it as a result of roll formation, and causing the paper to form a free arch which extends from the feeding means to the delivery opening and maintaining said 5 arch by force applied only against that surface of the paper which was inside when on the roll, and with the force applied at two points which substantially correspond to the bases of the arch, and while so maintaining the arched condition 10 causing the leading end of the paper to project through the opening in opposition to the upright wall, and with that surface which faced the supply roll, facing the user.

3. A paper cabinet having a delivery opening 15 and an upright wall therebelow, feeding means adjacent said delivery opening, a paper supply roll from which the paper leads to the feeding means, guiding means with which the free end of the paper engages and by which the paper substantially immediately after it leaves the feeding means and as it approaches the opening is automatically gradually flexed in a direction opposite to the direction of the curl which has been given the paper as a result of roll formation, said guiding means acting to form and maintain a free arch which extends from said feeding means to said delivery opening and below said guiding means, and said guiding means acting only on that face of the paper which was inside when on the roll, and said paper being fed only by said feeding means to lie freely pendent below the opening and in opposition to said upright wall, said guiding means also acting to cause that surface of the paper that faced the supply roll to 30 face the user.

4. In a dispensing cabinet having a delivery opening and an upright wall therebelow, feeding means, a paper supply roll from which the paper leads to the feeding means, guiding means acting 40 on the free leading end of the paper substantially immediately after it leaves the feeding means and until it is delivered through the opening and adapted to automatically gradually flex the paper in a direction opposite to the direction of the curl 45 given the paper as a result of roll formation and in a manner to form a free arch between the feeding means and opening, which is maintained by engagement of the paper with the guiding means at two spaced points which correspond substantially to the bases of the arch, said guiding means also serving to cause the paper to be projected through the opening in pendent opposition to 50 said upright face, and so that the surface which faced the supply roll, faces the user, whereby 55 the curling tendency of the paper as modified by the guiding means causes the paper to remain spaced from said upright wall.

FRANK G. STEINER.
